UNITED STATES PATENT OFFICE.

ANNA S. RIDENOUR, OF ATLANTIC CITY, NEW JERSEY.

BOOK-MARKER.

1,100,780.

Specification of Letters Patent. Patented June 23, 1914.

Application filed May 29, 1913. Serial No. 770,678.

To all whom it may concern:

Be it known that I, ANNA S. RIDENOUR, a citizen of the United States, residing at Atlantic City, in the county of Atlantic and 5 State of New Jersey, have invented a new and useful Book-Marker, of which the following is a specification.

My invention relates to a book marker having a head, an indicating or leaf-turning 10 arm, and a loop cord, the head being provided with incisions or slits for detachably connecting thereto the loop cord which retains the marker between the leaves of a book, the loop cord being held in the head 15 of the marker by the clasping engagement or contact of the edges of the incisions or slits, and the objects of my invention are to provide, first, a book marker that may be readily attached to or removed from a book 20 without injury to the leaves, cover or any portion of the book, second, a book marker that will remain securely in position in the book, third, a book marker which may be constantly used without injury to the leaves, 25 cover or any part of the book, fourth, a book marker which may be used as an individual marker or in series, each one of the series having a reference numeral, or other indicating means, to a page, section or line 30 of a reference book or guide.

I attain these objects by the device illustrated in the accompanying drawings in which—

Figure 1, is a perspective view of an open 35 book showing my book marker in place therein. Fig. 2, is a perspective view of a closed book showing on the back or hinge thereof, the loop cords of a plurality or series of my book markers in place within 40 the book. Fig. 3, is a face view of my book marker.

Similar numerals refer to similar parts throughout the several views.

My book marker, which is made of any 45 suitable flexible material, preferably celluloid, comprises a head, 10, an indicating or leaf-turning arm, 11, and a loop cord, 12. The head, 10, is rigidly attached to the indicating arm, 11, preferably by one piece 50 construction, at right angles to the longitudinal line of the indicating arm, 11, reference being had to my book marker as being in normal position in a book, so that an equal portion of the head, 10, extends above

and below the longitudinal line of said arm. 55 The head, 10, is shown in the drawings as much less in length than the indicating arm, 11, but the difference in length between the head and the indicating arm need not be so great as shown, provided the head, 10, is 60 not extended above or below the top and bottom of the page of the book in which my marker is used. The head, 10, is provided with an incision or slit, 13, in each of its said upper and lower portions to retain the loop 65 cord, 12, hereinafter described.

The incisions or slits, 13, are preferably cut at an angle to the longitudinal line of the head, 10, the better to retain or hold the loop cord, 12, by the clasping engagement or 70 contact of the sides of the incisions or slits, 13, with the loop cord against the upward and downward strain on the loop cord.

The indicating arm, 11, is in length slightly more than the width of the page of 75 the book, a portion of the arm, 11, being extended beyond the outer edge of the leaf of the book to provide a means by which to grasp the indicating arm, 11, to turn the leaves and also to provide space on which 80 to place a reference numeral or other indicating character to permit my book marker to be used in series in connection with a reference book or guide.

The loop cord 12, is of sufficient length to 85 allow one end thereof to be passed twice around the lower portion of the head, 10, and twice inserted in the incision or slit, 13, thereof to serve as a fixed attachment of the loop cord, 12, to the head, 10, while the remainder of the loop cord, 12, is carried 90 around and over the back or hinge of the book to the top thereof and then down between the leaves to the incision or slit, 13, in the upper portion of the head, 10, for insertion therein once, to permit ready detachment of this end of the loop cord, 12, from the head, 10, for removal of the marker from 95 between the leaves.

In use my book marker is placed between 100 the leaves of a book so that the head, 10, is adjacent to the back or hinge of the book in the vertical line of the book, while the indicating arm, 11, extends at right angles thereto, the head, 10, being held in place in 105 the book by the loop cord, 12, attached to the head, 10, as above described, my book marker being adapted as set forth to use as an in-

dividual marker or in series and to the accomplishment of the objects hereinbefore stated.

Having fully described my invention I claim:—

1. A book marker comprising a head, an indicating arm, and a free ended cord, the head being of less length than the indicating arm and arranged at right angles thereto and extending above and below the same and having incisions or slits for detachably retaining the free ends of the cord by the clasping engagement of the edges of the incisions or slits.
- 10 2. A book marker comprising a head, an

indicating arm, and a free ended cord, the head and indicating arm being of one piece construction, the head being of less length than the indicating arm and arranged at right angles thereto and extending above 20 and below the same and having incisions or slits cut at an angle to the longitudinal line of the head for detachably retaining the free ends of the cord by the clasping engagement of the edge of the incisions or slits.

ANNA S. RIDENOUR.
